CLAIM

The ornamental design for an electronic animal correction device, as shown and described.

DESCRIPTION

FIG. 1 is a front, left, top perspective view showing our new design for an electronic animal correction device in its environment of use.

FIG. 2 is a front view of the electronic animal correction device

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is another front, left top perspective view thereof;

FIG. 9 is a front, right bottom perspective view thereof;

FIG. 10 is a rear, left top perspective view thereof; and,

FIG. 11 is a rear, right bottom perspective view thereof.

The angled/diagonal parallel shading lines of the corner rim portion in the drawings represent translucency.

The broken lines on the electronic animal correction device depict portions that form no part of the claim. The broken line illustrating a collar strap in FIG. 1 illustrates the environmental structure and forms no part of the claim.
